UNITED STATES PATENT OFFICE

2,451,766

DENTAL APPLIANCE

Francis J. Meylan, Scranton, Pa.

Application June 17, 1947, Serial No. 735,068

5 Claims. (Cl. 32—19)

1

This invention relates to the art of prosthetic dentistry and is concerned particularly with an apparatus for recording a bite and at the same time stimulating the muscles of mastication in order that the upper and lower casts may be properly related to each other and therefore these casts will assume the same relation as the upper and lower jaws when mounted on an articulator.

This invention is an improvement over the construction shown and claimed in my Patent 2,245,288 issued June 10, 1941, and while it may be used to record a bite in the same manner as that disclosed in said patent, its primary function is to stimulate the muscles of mastication, to properly balance the casts and to cause proper intrusion of the condyle into the glenoid fossa.

While possessing all of the advantages of the construction shown in my patent, the present invention deals with a construction that is more accurate in use and which is more readily manipulated by the dentist when mounted in the oral cavity of the patient.

In the aforesaid patent, emphasis was laid on the fact that a heavy spring was interposed between the maxilla and the mandible and positioned relative thereto so that in the act of taking a bite, the condyles are forced to their highest point in the glenoid fossae to insure true centric occlusion.

It has been found, however, that in many patients the normal position of the condyle in the glenoid fossae is not necessarily at the highest point therein and the present invention, therefore, is to cause intrusion of the condyle into the glenoid fossa so that it will attain its normal position in the act of biting whether true centric occlusion is present or not.

It is to be understood, of course, that the present invention can function in the same manner as that disclosed in the patent, that is, to record the movement of the mandible on a wafer as disclosed in the patent, but in using the patented construction, it was found that in many instances, the use of the multiple teeth on the rack did not accomplish the desired results because the points between open and closed condition of the capsule either were passed to completely closed position or the patient was left with a bite which was too far open.

The present invention eliminates such objection and relies upon normal intrusion of the condyles into the glenoid fossae, after the vertical dimension has been secured by means of customary measurements.

In the act of biting, contact is made between

2

the upper and lower teeth initially at a point adjacent to the first bicuspids, after which increased biting force causes the mandible to fulcrum about this point, progressively bringing the posterior teeth into occlusion, due to the action of the main masticating muscles, such as the masseter, internal pterygoid, and temporal muscles, which force the condyles into the glenoid fossae and the present invention is designed primarily to stimulate the actions of these muscles so that the condyle assumes the normal position for the particular patient in the act of biting.

Since the apparatus of my patent and of the present invention lies wholly within the oral cavity, it must be of such simple construction that it can be readily manipulated by the fingers of the dentist and the present invention improves the construction of my patent in order to facilitate the necessary manipulations.

20 Referring now to the drawings in which I have illustrated the preferred embodiment of my invention and in which corresponding parts are similarly numbered:

Fig. 1 is a vertical sectional view of my invention.

Fig. 2 is a side elevation of the capsule.

Fig. 3 is a horizontal sectional view taken on the line 3—3 of Fig. 2.

Fig. 4 is a view of the capsule with the parts disassembled to show the interior construction.

Fig. 5 is a side elevation of the inner cup member.

Fig. 6 is a horizontal sectional view taken on the line 6—6 of Fig. 5.

35 With particular reference to the drawing, the present invention discloses an upper plate 1 and a lower plate 2 which may be of vulcanite, shellac, or other suitable material, shaped from casts of the gum ridges of the maxilla and mandible, respectively.

Secured to the upper plate 1 is a capsule 3 which consists of an inner inverted cup 4 and an outer cup 5 telescoping over the inner cup and having a closed lower end 6 provided with a stylus 7.

45 The inner cup member 4 has a closed upper end 8 provided with a threaded aperture 9 to receive the shank of a screw 10 which is provided with a slotted head 11 secured to the upper plate 1 by means of suitable molding compound 12.

50 Interposed between the flat head 11 and the closed end 8 of the cup 4 is a locking element 13 threaded on the shank 10 and engaging the closed end of the inner capsule so as to retain the inner cup in properly adjusted position toward or away

55 from the upper plate 1.

The lower plate 2 is provided with a table 14 on which is carried a wax wafer 15 having a thin, flexible foil facing strip 16 similar to that shown in said patent.

The wafer 15 and foil 16 are secured to the table 14 in any suitable manner, and must be located centrally below the stylus 7 so that in the act of biting the stylus bites into the wafer by forcing the flexible foil disc into the same so that if the device is to be used as a recording instrument, movement of the mandible will cause the stylus to scribe the well-known Gothic arch or if recording is not desired, the forcing of the stylus into the wax wafer prevents undue slipping of the stylus from its proper position.

Interposed between the inner cup member 4 and the outer cup 5 is a flat helical spring 17 with the convolutions thereof in frictional engagement with one end of the spring bearing upon the closed end of the inner cup 4 and the other end bearing upon the closed end of the outer cup 5 and normally biasing the cups away from each other.

In order that the cups may not be completely separated from each other, the inner cup 4 is provided at its lower end with a flange 18 providing an annular shoulder 19 and the lower cup 5 is provided with spring-pressed detents 20 and 21, here shown as two in number and lying at diametrically opposite points on the circumference of the outer cup 5.

The detents 20 and 21 project through apertures 22 and 23 in the side walls of the lower cup 5 and engage the shoulder 19 on the upper cup 4, thereby arresting complete separating movement of the cups relative to each other.

The detents 20 and 21 are carried at the free ends of semi-circular flat springs 24 and 25 which encircle the outer cup and are secured thereto by screws 26 and 27.

With the inner cup 4 and outer cup 5 in the position shown in Fig. 1, the capsule 3 is in its fully expanded position and in such position it is secured to the upper plate 1, the plates placed in the mouth of the patient and the lower wafer positioned below the stylus 7.

The capsule 3 is then adjusted along the screw threaded stem 10 until the stylus contacts the foil disc 16, after which the patient is instructed to bite. Such action results in collapsing the spring 17 and imparting telescoping movement between the cups 4 and 5. In this action the detents 20 and 21 ride upwardly on the outer surface of the inner cup 4 and up the inclined face 29 which extends circumferentially about the inner cup, after which they snap behind the annular shoulder 30 formed by the outwardly inclined surface 29.

The act of collapsing the capsule is against the force of the spring 17 and consequently the jaws are placed under load with the result that the condyle is forced to its normal position of intrusion within the glenoid fossa.

When the detents 20 and 21 are in engagement with the annular shoulder 30, the capsule is in its fully contracted position and in order that the capsule may again be readily operated so as to assume its expanded condition, there are provided diametrically opposed, flat, land portions 31 and 32 which intersect the inclined surface 29 and permit the detents to be returned to position 70 in engagement with the shoulder 19 on the inner cup.

This is made possible by grasping the outer cup at the knurled band portion 33 and rotating the same on the inner cup 4 until the detents align 75

with the land portions 31 and 32 at which time expansion of the spring 17 will cause separating movement between the cups 4 and 5.

When it is desired to collapse and lock the capsule in a subsequent operation, it is merely necessary to rotate the lower cup 5 to move the detents 20 and 21 out of alignment with the land portions 31 and 32 so that when a bite is again taken, the detents will ride over the inclined surface 29 and lock behind the annular shoulder 30.

By the foregoing construction it will be seen that a more simplified operation is possible and that the cups of the capsule may be much more readily manipulated to permit operation of the cups than is possible in the construction of my patent.

It will be further seen that the present invention may be used to obtain all of the advantages of the patented construction, but that it eliminates some of the defects.

I claim:

1. In a device of the class described comprising a plate carried by the maxilla and a plate carried by the mandible, a capsule mounted on one of said plates comprising telescoping cup-shaped members and a spring interposed therebetween normally biasing the members away from each other, cooperating means on the cup-shaped members for locking the cups in contracted position upon movement of the cups toward each other, one of said cup-shaped members being rotatable relative to the other to release said locking means and permit expansion of the members under the action of the spring.

2. In a device of the class described comprising a plate carried by the maxilla and a plate carried by the mandible, a capsule mounted on one of said plates comprising an inner inverted cup and an outer cup telescoped over the inverted cup and spring biased away from each other, said outer cup being slidably and rotatably carried by the inner cup, latch means carried by the outer cup and engaging the inner cup to hold the cups in contracted position and means for rotating the outer cup and latch to release the latch means and permit separating movement thereof under the action of the spring.

3. In a device of the class described comprising a plate carried by the maxilla and a plate carried by the mandible, a capsule mounted on the maxillary plate comprising telescoping upper and lower cup-shaped members normally biased to separated position, an annular flange at the lower end of the upper cup and spring pressed detents carried by said lower cup and engaging said flange to prevent complete separation of said cup members, an annular, outwardly and upwardly inclined surface on said inner cup-shaped member spaced above said flange and forming an annular shoulder, said detents engaging behind said shoulder when the cups are moved together to hold the same in retracted position.

4. In a device of the class described comprising a plate carried by the maxilla and a plate carried by the mandible, a capsule mounted on the maxillary plate comprising telescoping upper and lower cup-shaped members normally biased to separated position, an annular flange at the lower end of the upper cup and spring pressed detents carried by said lower cup and engaging said flange to prevent complete separation of said cup members, an annular, outwardly and upwardly inclined surface on said inner cup-shaped member spaced above said flange and forming an annular shoulder, said detents engaging behind said

shoulder when the cups are moved together to hold the same in retracted position, and flat lands intersecting said inclined surface and shoulder and permitting expansion of the cups when the detents are aligned therewith.

5. In a device of the class described, comprising a plate carried by the maxilla and a plate carried by the mandible, a capsule mounted on one of said plates and comprising an inverted cup and a cup slidably telescoping therewith and having a spring interposed therebetween normally biasing the cups away from each other, spaced an-

5
10
6
nular shoulders on said inverted cup and latch means carried by said cup and engaging said shoulders to latch the cups in contracted or expanded position, said latch means comprising semi-circular, flat, leaf springs encircling the cup member and having one end secured thereto, the free ends of said springs carrying latching detents projecting through said cup and into the path of movement of said shoulders.
